UNITED STATES PATENT OFFICE.

ARDENUS R. FREE, OF PEEKSKILL, NEW YORK.

TYPE-WRITER.

SPECIFICATION forming part of Letters Patent No. 698,487, dated April 29, 1902.

Application filed December 6, 1899. Serial No. 739,426. (No model.)

To all whom it may concern:

Be it known that I, ARDENUS R. FREE, a citizen of the United States, and a resident of Peekskill, in the county of Westchester and State of New York, have invented certain new and useful Improvements in Type-Writers, of which the following is a specification.

My invention relates to type-writers, and has for its object the saving of time occupied in placing the paper to be written upon in position in the machine. The object is attained by the means set forth in this specification and the accompanying drawings, which form a part thereof.

15 My first reference will be to the drawings, in which like characters refer to similar parts throughout the several views.

Figure I represents the upper portion of a type-writer having my invention attached thereto. Fig. II is a plan of Fig. I upon a larger scale than said figure and includes the type-supporting disk, showing the position of my attachment in its relation to the part of the type-writer shown. Fig. III is a back view of my attachment. Fig. IV is a sectional view through line *x*, Fig. II, showing how my attachment is connected with the pivotal bar of the platen. Figs. V and VI and VII are details relating to Fig. III. Fig. VIII illustrates the application of a tension to the paper-roller used in my attachment. Fig. IX is a section of a roll of copying-paper. Fig. X represents a ball-bearing applied to a traveling wheel in my attachment.

35 This invention consists of an attachment for type-writers for carrying a roll or web of paper, so that as a sheet is printed upon it may be torn off, leaving the machine already "threaded" with another sheet. My object 40 is to prepare paper in long strips, perforated or otherwise fixed to readily separate in sheets, the sheets printed as letter, bill, or statement heads and then wound into rolls. To make these sheets available, I make an attachment for supporting the paper in the roll and connect the roll-carriage with the platen-carrying frame in such a manner that the roll of paper will have the same lateral movement as the platen. This device may be 45 applied to any make or style of type-writer; but for convenience I have shown it as applied to the type-writer known as the "Calif-

graph." Fig. I of my drawings shows enough of the top of the machine to make my invention clear. 11 represent an end of the frame 55 that supports the type-disk 2 and the platen *p*. Posts 3 on each end of the machine, Figs. I and II, support a rod *k*, on which blocks 4 (see Figs. I and V) freely move, and to these blocks the escapement-bars *m n* are attached 60 and also the rod *f*. The platen-frame is pivoted on the rod *f* on its side and travels on the roller *i* and track *j* in front, as shown in Fig. I. The horizontal movement of the platen-frame is upon the rod *k* and its upward movement is on the rod *f*.

To support the roll of printing-paper, a frame is provided, consisting of strip-steel *b* bent into shape, as shown in Figs. I and II. The free ends of this frame *b* are, as shown, 70 provided with hubs *b' b'*, which are slipped on the rod *f* between the bar *g'* and a collar that lies next the lever *s* just inside the bar *g*. The outer end of the frame *b* is provided with a roller *c*, that travels on a track *d*. The 75 track *d* is supported by brackets *e*, that are affixed to the end frames 1 of the type-writer. Notches or journal-bearings 5 are provided in the sides of the frame *b* to receive the journals 6 of the shaft 7, on which the roll of paper *a* is placed.

The apron *h* (shown in Fig. I) for holding the paper in position against the platen is omitted from Fig. II for the purpose of more clearly showing the connection of the paper-carriage to the platen-frame. It will be apparent that the roll-carrier will in no wise interfere with the platen. In Fig. I it is also clear that the paper-roll carrier is free from interference with the moving parts connected 85 with the platen, as all the parts of this attachment are adapted to stand clear of the lever *r*, which moves the platen-frame.

As the roll of paper and its supporting-frame follows the horizontal movements of 95 the platen some additional strain is put upon the platen-propelling mechanism; but this strain is reduced to a minimum by placing the roll of paper nearer the traveler *c* than it is to the carriage and by mounting the traveler on ball-bearings, as shown in Fig. X. The traveler is grooved and rides on the rail *d*.

The operation of the device is simple. As shown in Fig. I, when a roll of paper is placed

in the frame *b b* the paper is drawn around the platen and may be torn off in lengths to suit if the paper is not perforated; otherwise each sheet would be drawn through to the 5 next perforation and there torn off, so that there would always be a sheet ready in the machine.

In Fig. I the axle upon which the paper-roll is placed is shown as simply resting in 10 deep slots in the supporting-frame *bb*. When a roll is full, its weight would retain it in its place; but as the roll grew lighter from use of the paper some means would be required to keep the roll in its place, and at times some 15 tension may be needed to prevent a too easy unrolling of the paper. Such means are shown in Fig. VIII, in which the journal 5 is not so deeply seated, its upper surface lying a little above the top edge of the frame *b*. A spring 15 20 is fastened to the frame and reaches over the journal, as at 17, and the spring being given a strong initial pressure the pressure is regulated by means of the thumb-screw 16.

The paper employed with this device, as 25 has been explained, would be provided in rolls, and these rolls would be adapted to being placed on the spindle or shaft 7, having a hole through the center just a proper size to receive the shaft. Naturally in the preparation of the shafts and rolls a standard of 30 sizes would be adopted, so that any of the prepared rolls would fit any of the attachments.

To facilitate the tearing off of sheets or for 35 tearing sheets off of rolls that are not perforated, a device is shown in Fig. II. The spring 20, Fig. II, on the type-writer shown is used as a guide to direct the paper over the platen as it comes through the machine. The hubs 21 21 support a scale on the face of 40 the platen. By attaching projections 22 22, Fig. II, to the said hubs 21 21 they and the central spring 20 may be made to support a strip of metal 23 across the face of the platen at a height that will leave a printed letter or 45 bill head in the machine adjusted to the dating-line for the next letter, bill, or other matter. By pressing the fingers upon the strip 23 during the act of tearing, imperforated paper may be readily separated from the roll.

The strip 23 is at a point high enough not to 50 interfere with intelligible reading of what has been printed.

This device may be made so as to be quickly added to or taken from any type-writer. In the one shown, for instance, Fig. IV shows the bar 55 *b* to be rigidly fast to the rail *f*. Figs. V, VI, and VII show how the bar *b* may be attached to the rail *f* so as to be readily removable. The hole to receive the rail *f* is elongated, (see Fig. V,) and the bar is partially cut away 60 on the under side, as at 10, making a hook 11, that may be placed over the rail without separating any of the platen-frame's parts. In order to secure the bar in the position shown in Fig. V, a plate 12, Fig. VI, with a lengthened hole 13 for a screw 14, is provided. When the plate 12 is pushed against the rail, as in Fig. VI, and fastened by the screw 14, this connection is complete. Fig. VII is a view of the under side of this connection. As the 70 brackets are fastened with screws, (or they may be secured by means of some one of the many means of clamping,) they may be easily detached.

Having described my invention, what I 75 claim, and desire to secure by Letters Patent, is—

The combination with the frame and platen of a type-writer of brackets *e* attached to the frame of the machine and supporting a track 80 *d*, a paper-roll carrier *b* with arms removably hooked upon the platen-carrying rod *f* embracing the platen-frame between them as described, the outer central end of said frame having a roller *c* that rides upon the track *d*, 85 the paper-roll, supported upon the carrier *b* by journals 5 as shown, and a spring 15 resting upon one of said journals and having a strong initial pressure regulable by means of a screw 16, substantially as herein set forth. 90

Signed at Peekskill, in the county of Westchester and State of New York, this 21st day of November, A. D. 1899.
